UNITED STATES PATENT OFFICE.

JOHN F. HORNBERGER, OF LAWRENCEBURG, INDIANA, ASSIGNOR OF ONE-HALF TO E. & J. SCHWERKERT, OF CINCINNATI, OHIO.

EAR-PIERCER.

SPECIFICATION forming part of Letters Patent No. 460,138, dated September 29, 1891.

Application filed November 19, 1890. Serial No. 371,920. (No model.)

To all whom it may concern:

Be it known that I, JOHN F. HORNBERGER, a citizen of the United States, and a resident of the city of Lawrenceburg, in the county of 5 Dearborn and State of Indiana, have invented certain new and useful Improvements in Devices for Piercing the Ear, of which the following is a specification.

The several features of my invention and 10 the various advantages arising from their use, conjointly or otherwise, will be apparent from the following description and claim.

In the accompanying drawings, making a part of this specification, and to which reference is hereby made, Figure 1 is a side view 15 of an ear-piercer embodying my invention, all of the parts being shown in elevation with the exception of the pointed cap. A central longitudinal section of this cap is here shown 20 in position for piercing the ear. One form of ear-ring is also shown in the position it occupies while the ear is being pierced. In Fig. 2 the shank is shown in side elevation and the handle attached thereto is shown in 25 central longitudinal section. The rear end of the handle is broken off to better afford room for displaying the shank and pointed cap as separated the one from the other. A central or axial section of the pointed cap is 30 here shown. Fig. 3 is a transverse section taken through the shank and pointed cap when together. This section is taken at the dotted line 3 3 of Fig. 1, but the ear-ring shown in Fig. 1 is omitted from this view. Fig. 4 is 35 a view in perspective of the shank, showing the side of it and those ends of it which face toward the left hand in Fig. 1.

For the purposes of perspicuity in description the various devices and things shown in 40 all of these figures are therein shown of a larger size than they actually are.

A indicates the shank, having a channel B. This channel extends longitudinally in the shank to one end thereof. The other end portion of the shank may be used as the handle, and in such event will preferably be solid, thus forming the shank portion C, as shown.

As the shank A is in fact of a very small thickness or diameter, it is desirable that the 45 handle be thicker in order that it may present

a better hold for the fingers of the hand of the operator who does the piercing of the ear. I have therefore provided a handle, as D, preferably made of wood. The shank portions A C are preferably of metal, and a convenient and practicable mode of uniting them to the handle consists, as shown, in inserting the free end of portion C in the end of the handle D. A cap E is also present. One end F of this cap E is pointed. The other end is 60 open and is the termination of an opening G, extending into the cap. The width of this opening is such as to admit of the channeled end of the shank A C being passed into it and fitting closely therein. 65

In practice that portion, as H, of the ear-ring I which is to be placed in the orifice to be formed in the ear is located in the recess B of the shank, the free end of the said portion H being near the free end of the shank 70 A, substantially as shown in Fig. 1. The cap E is now slipped over the said ends of the shank A and ear-ring until these ends come against the inner end of the opening G—that is to say, against the solid portion F of the 75 said cap E. The operator then places the point of end F against that part of the lobe of the ear which is to be pierced, and then at a single stroke pierces the ear, carrying the cap E through the ear, and consequently also 80 carrying the wire or portion H of the ear-ring and the forward portion of the shank A through the ear as far as the dotted line 4 4 of Fig. 1. The cap E is now moved forward and thus withdrawn from the shank A. The 85 shank A is now moved backward, and at the same time the ear-ring is held still in relation to the ear. This operation withdraws the shank A from the ear and leaves the portion H of the ear-ring in the ear. The ear-ring, if 90 provided with a lock or catch, as J, may now be locked in the usual well-known manner. It cannot then slip out of the opening in the ear.

My improved ear-piercer is simple of construction, economical of manufacture, and 95 durable. It is easily manipulated.

The piercing of the ear operates to introduce the ear-ring into the opening made by the operation of piercing, and also carries a portion of the ear-ring through the said open- 100

ing. Thus a single operation suffices to pierce the ear and pass the ear-ring through the ear, and obviates the necessity of subjecting the patient to a second painful operation.

5 What I claim as new and of my invention, and desire to secure by Letters Patent, is—

In an ear-piercer, a rod or shank A, provided with recess or channel B, and the cap

E, having a point F, the cap being adapted to slide over the said shank, substantially as 10 and for the purposes specified.

JOHN F. HORNBERGER.
